E. DEACON,

Fishing-Rod Reel.

No 16,626.

Patented Feb. 19, 1857.

Fig. 1.

Fig. 2.

UNITED STATES PATENT OFFICE.

EDWARD DEACON, OF BROOKLYN, NEW YORK, ASSIGNOR TO JOHN WARREN.

IMPROVEMENT IN FISHING-ROD REELS.

Specification forming part of Letters Patent No. 16,626, dated February 10, 1857.

To all whom it may concern:

Be it known that I, EDWARD DEACON, of Brooklyn, in the county of Kings and State of New York, have invented a new and useful Improvement in Reels for Fishing-Rods; and I do hereby declare that the following is a full, clear, and exact description of the same, reference being had to the accompanying drawings, making a part of this specification, in which—

Figure 1 is a central section of the reel-frame, the sleeve which encompasses the crank-shaft being also bisected, but the reel and gearing not being bisected. Fig. 2 is a detached longitudinal section of the sleeve.

This invention relates to an improvement in reels for fishing-rods, by which improvement the crank-shaft may be readily connected with and disconnected from the reel-shaft, as desired, so that, in throwing out the line, the reel, being disconnected from the crank-shaft, will have no friction to overcome but that produced by its own journals.

The invention consists in placing a sleeve upon the crank-shaft, said sleeve being fitted within a socket attached to the reel-frame, and having a slot made in it, in which slot a pin secured within the socket fits. By operating or sliding the sleeve the crank-shaft is also moved, and the toothed wheel upon it thrown in and out of gear with the pinion on the reel-shaft.

To enable those skilled in the art to fully understand and construct my invention, I will proceed to describe it.

A represents the reel, which is fitted within a frame formed of two plates, *a a*, connected by rods *b*. The reel and frame are of the usual construction, and therefore do not require a minute description.

The frame has the usual case or box *B* at one side, to inclose the gearing *C D*, *C* being the pinion on the end of the shaft *E* of the reel, and *D* is the toothed wheel on the inner end of the crank-shaft *F*.

On the crank-shaft *F* a sleeve, *G*, is placed, and the sleeve is fitted within a socket, *c*, attached to the outer side of the box *B*. The sleeve *G* has a slot, *d*, made in it, the ends of the slot having lateral or side notches, *e e*, at opposite sides, as shown clearly in Fig. 2. A

pin, *f*, is placed in the socket *c*, said pin fitting in the slot *d*.

H represents the crank, which is placed on the shaft *F* and secured thereon by a nut, *g*, on the outer end of the shaft *F*, the crank being pressed snugly up against a shoulder on the crank-shaft *F*. The outer end of the sleeve *G* has a milled flange, *h*, upon it.

The crank-shaft *F* is shoved in or out, so that its wheel *D* may be in or out of gear with the pinion *C* of the reel-shaft *E* by merely shoving the sleeve *G* inward or drawing it outward. The notches *e e* serve to keep or lock the wheel *D* in either position—that is, either in or out of gear—the collar being turned on the shaft *E*, so that the pin *f* in the socket will fit in the notches at either end of the slot *d*. The inner end of the shaft *F* fits or works in a step or bearing, *i*, in the adjoining plate *a*.

I am aware that a patent was granted to John N. Bailey for reels so constructed that the crank-shaft could be thrown in and out of gear with the reel-shaft; but a spring was employed and so connected with the crank-shaft as to keep it thrown out of gear or disconnected from the reel-shaft. Consequently, to connect the crank-shaft with the reel-shaft the crank-shaft required to be pressed inward by the hand as the crank was turned. The pressure upon the crank renders the winding up of the line upon the reel a difficult operation, and a person is liable to forget that pressure upon the crank is requisite in order to connect the crank with the reel-shaft. The spring also is liable to lose its elasticity, and the parts may thus be rendered inoperative.

Having thus described my invention, what I claim as new, and desire to secure by Letters Patent, is—

Connecting the crank-shaft *F* with the reel-shaft *E*, and also disconnecting it therefrom, by means of the slotted sleeve *G*, placed or fitted upon the shaft *F* and within the socket *c*, substantially as herein shown and described.

EDWD. DEACON.
